DESIGN FOR A VENDING MACHINE

Benjamin W. Fry, St. Louis, Mo.

Application January 25, 1936, Serial No. 60,802

Term of patent 7 years

To all whom it may concern:

Be it known that I, Benjamin W. Fry, a citizen of the United States of America, residing in the city of St. Louis, in the State of Missouri, have invented a new, original, and ornamental Design for a Vending Machine, of which the following is a specification, reference being had to the accompanying drawing, forming a part thereof.

The figure is a perspective view of a vending machine showing my new design.

The opposite side of the design is the same in appearance as the side shown in the figure.

I claim:

The ornamental design for a vending machine, as shown and described.

BENJAMIN W. FRY.
